UNITED STATES PATENT OFFICE.

RICHARD H. SOULE, OF BALTIMORE, MARYLAND.

PRESSURE-REGULATING VALVE.

SPECIFICATION forming part of Letters Patent No. 237,624, dated February 8, 1881.

Application filed May 6, 1880. (No model.)

To all whom it may concern:

Be it known that I, RICHARD H. SOULE, a citizen of the United States, residing at Baltimore, in the county of Baltimore and State of Maryland, have invented certain new and useful Improvements in Pressure-Regulating Valves; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification, in which—

15 Figure 1 represents a side elevation of a device embodying my invention. Fig. 2 represents a central vertical section of the same, showing internal construction.

20 My invention relates to that class of valves or other cut-offs located in pipes or other closed conduits, by means of which the supply through said pipes or conduits shall be automatically cut off when any desired limit of pressure has been attained.

25 Although my invention is designed more particularly for use in connection with the system of air, steam, vacuum, and other pneumatic brakes upon railroad-trains, it will be obvious that it is applicable to a great variety 30 of other useful purposes. One of the troubles in the use of these power-brakes is the frequent sliding of wheels due to overpressure of air, steam, or other fluid in the brake-cylinders. The pressure at which the wheels of a given 35 car will slide is dependent on several factors, such as the weight of the car, the leverages of the brake-gear, and the area of the piston of the brake-cylinder. It therefore frequently occurs that in a given train the sliding pressures vary largely for the different cars. Now, 40

the present prevailing custom is to endeavor to limit the maximum pressure of air, steam, or other fluid throughout the train, by means either of a safety relief-valve or of judgment 45 exercised on the part of the engineer in regulating the admission of fluid under pressure to a point slightly below the least of the sliding pressures of the cars; but this practice is objectionable for two reasons. In the first 50 place, under those conditions, an engineer is very liable to overcharge the brake-cylinders,

and so slide and ruin the wheels. In the second place the greatest efficiency of the braking apparatus is not attained, because the maximum pressure of all the cars is limited by the case 55 of that one car whose sliding pressure is the lowest of all.

By the use of my improvement, hereinafter described, each brake-cylinder could be charged nearly up to the sliding pressure of the car to 60 which the valve, respectively, is attached, independently of the sliding pressure of any and every other car, and so the maximum efficiency of the whole brake apparatus would be realized, while it would also be rendered im- 65 possible that any of the wheels of the cars of the train should be slid.

To accomplish this desideratum and obviate the defects in the manner of braking trains, as before set forth, I have devised my present 70 improvement, which consists in certain new and useful peculiarities of construction and relative arrangements or combination of parts, all of which will be fully described, and then pointed out in the claims.

75 Referring to the drawings, A' represents a cylinder, screw-threaded at both ends, and provided with a valve-chamber, a, piston-chamber e, and air-chamber e', having an opening, e', for the escape of air in the downward movement of the piston.

A represents the inlet to the valve-chamber, and B the outlet. All air, steam, or other fluid supplied to the brake-cylinder must pass through the valve-chamber a in the direction 85 of the arrows. On the brakes being released, the air, steam, or other fluid passes from the brake-cylinder out through the valve-chamber a in a direction opposite to that indicated by the arrows.

90 The construction of the apparatus, as shown in the drawings, embodies a valve, C, mounted on a spindle, D, which may have, under certain conditions, a limited amount of motion in the direction of its length, which will herein- 95 after be set forth. Lower down on the spindle is mounted a piston, E, having a suitable packing, and which fits a truly cylindrical chamber, e, below the level of the outlet B. Intermediate between the inlet A and outlet 100 B, in the chamber a, is a partition, F, in which is formed the seat c of the valve C. The spin-

dle D has formed on it, near its lower end, a collar, G, which normally bears against the under side of the partition H, formed in the casing, and which is pierced with a central opening, through which the spindle D plays. Between the collar G and the collar I, on the lower spring-plug L, is a spring, M, which may be set to any desired degree of compression by the adjusting-screw J. This screw J works 5 through the screw-plug N of the casing. The valve C is mounted upon the upper end of spindle D, and its valve-stem c' is received into a guide or way formed on the lower side of the screw-cap O.

15 The operation of the device is as follows: The air, steam, or other fluid to be supplied to the brake-cylinder or diaphragm passes from the inlet A through the valve-chamber a, and under the valve C to the outlet B, and by 20 it to the brake-cylinder. The supply of air, steam, gas, or other fluid continuing to pass in through the apparatus, there will be no alteration in the relative positions of the different parts of the apparatus until the pressure 25 on the upper side of the piston E shall become equal to the tension of the spring M, which is bearing against the under side of the collar G. The supply of fluid still continuing under pressure, the gradual downward movement of 30 the spindle D and its attached parts will ensue until the valve C becomes seated, and the supply through the valve and device thereby 35 shut off, after which there can be no further increase of pressure in the brake-cylinder or diaphragm or below the valve C. Above the valve C, however, the pressure may continue 40 to increase to any extent. Should the air, steam, or other fluid be exhausted from the chamber above the valve C, the latter would lift from its seat immediately after the pressures above and below the valve had become 45 equal to each other.

By means of the adjusting-screw J the tension of the spring M may be adjusted to any 50 desired point of cut-off—that is, the valve may be made to seat itself and prevent the further accumulation of pressure beneath it at any desired pressure.

Instead of a spring, some other mechanical 55 device might be used for affording the requisite

resistance to the downward movement of the valve.

The device would work with good results in a horizontal or other position, as may be deemed desirable.

55

K represents a lug attached to the casing, the object of which is to provide a means, in connection with the holes through it and the head of the adjusting-screw J, for introducing a seal or lock of any suitable form, whereby 60 any tampering with the valve by unauthorized persons would be made apparent.

I am aware that an automatic regulating-valve constructed with a diaphragm and provided with a spring-box, in combination with 65 a flexible diaphragm, a valve, and a connecting stem, as shown in Letters Patent granted to B. Holly for a regulating-valve for service-pipes, reissued May 23, 1871, No. 4,395, has heretofore been employed, and I therefore lay 70 no claim to such construction, my invention being confined to the details of construction pointed out in the claim, in which the flexible diaphragm of the invention disclaimed, which is liable to become loose and inoperative or 75 broken, is entirely dispensed with, and the parts so arranged as to render the construction different, and more effective and certain in their operation.

Having described my invention, what I 80 claim as new, and desire to secure by Letters Patent of the United States, is—

The combination, with the cylinder A', screw-threaded at both ends and provided 85 with the inlet and outlet pipes A B, valve-chamber a, having partition F, with valve-seat c, piston-chamber e, and air-chamber e', provided with the air-hole e², of the spindle D, carrying the piston E, valve C, and collar G, casing P, having stop-partition H, plug L, 90 having collar I, spring M, and adjusting-screw J, the whole constructed, arranged, and operated in the manner and for the purpose set forth.

In testimony whereof I affix my signature 95 in presence of two witnesses.

RICHARD H. SOULE.
